UNITED STATES PATENT OFFICE.

JOHN S. PESSENGER, OF BROOKLYN, NEW YORK.

STEAM-BOILER.

SPECIFICATION forming part of Letters Patent No. 319,120, dated June 2, 1885.

Application filed February 21, 1884. (No model.)

To all whom it may concern:

Be it known that I, JOHN S. PESSENGER, a citizen of the United States, residing at Brooklyn, in the county of Kings and State 5 of New York, have invented certain new and useful Improvements in Steam-Boilers, of which the following is a description.

My invention consists, essentially, of the combination, in a boiler-furnace, of fire-box 10 walls; also side walls back of the fire-box, and also the bridge-walls, either for an ordinary boiler of cylindrical form or a sectional boiler of any kind, made of coils of pipe in any form, with return-bends, elbows, and other connections inclosed either wholly or with some parts 15 left for access to the interior of the pipe by jackets of metal cast around the pipes, the objects being to provide furnace-walls in which much of the heat absorbed by the ordinary 20 walls will be utilized for generating steam, and which will add materially to the capacity of the boiler, and also to re-enforce the metal of the pipes with coverings of cast metal, for protection from the fire.

My invention also consists of an improved 25 contrivance of sectional boilers consisting wholly of coils thus incorporated in plates of metal cast around the pipes of the coils, all as hereinafter fully described, reference being 30 made to the accompanying drawings, in which—

Figure 1 is a longitudinal sectional elevation of a boiler having fire-box walls, also side walls back of the fire-box, and also the bridge-wall, 35 together with a sectional construction of the rest of the boiler, made of coils of pipes covered with metal cast around them, the section being on line *x x*, Fig. 5. Figs. 2 and 3 are details of a form of return-bend that I propose 40 to employ in the construction of the coils, said figures being made on an enlarged scale. Fig. 4 is a section across the front end of the boiler, with the upper section in end elevation on line *y y*, Fig. 1. Fig. 5 is a transverse section of 45 the boiler on the line *z z*, as seen looking toward the front from the rear.

I make the front wall, *a*, also the side walls, *b*, of the fire-box, also the side walls, *c*, back of the fire-box, and also the bridge-wall *d*, of 50 coils of steam-pipe *e*, incorporated in metal plates by casting the metal *f* forming the plates around the pipes of the coils, so that by causing the water to pass through these walls much of the heat which wastes in the ordinary

side walls will be utilized and the capacity of 55 the boiler for holding water and for generating steam will be correspondingly increased.

The coils may be made in any approved form, with elbows, T's, return-bends, and other connections or fittings of common form, 60 or with any specially-contrived fittings, and the coils for the respective walls may be incorporated in a single casting, as I have herein represented them, the said respective coils being suitably connected together and placed 65 in the mold suitably prepared for enveloping them all together by the casting of the plates, or the coils for the respective walls may be covered separately by the cast metal, said coils having suitable provision for making the 70 requisite connections for the circulation of the water. In this example I have represented the walls thus made integral with each other, including the bridge-wall, making the coil for the bridge-wall suitably for receiving the feed- 75 water at *h* and distributing it equally between the two side walls, *b*, and also through the two parts of the front wall, *a*, to the outlet *i* for delivering the hot water to the upper part of 80 the boiler through the steam-pipe *n*.

The bridge-wall coil is in this case made in two parts, for the purpose of effecting equal distribution of the water through both side walls of the fire-box, to which it delivers the water through the vertical pipes at the ends 85 of the horizontal pipes of said bridge-wall, and which discharge the water to the lowest pipes of the side walls, through which it first flows to the front of the fire-box, to and through the lower coils of the front wall, and thence 90 back and forth through coils of the front and side walls to the top of the same, where both side walls are connected by the upper pipe of the front wall, so that both side walls discharge into the outlet *i*, for being delivered 95 into the upper part of the boiler, which may be of the sectional type herein represented, or any other sectional form, or it may be an ordinary cylinder-boiler, and whether of sectional or cylindrical form, the side walls, *b*, 100 may be extended as much higher than herein represented as the nature of the case may require. For instance, in the case of a cylindrical boiler it would be desirable to extend the side walls up along the sides of the cylinder to the top or thereabout, in which case each side wall *b* would preferably have its own outlet *i* discharging into the cylinder, 105

but the front wall, *a*, would terminate under the front end of the cylinder. The coil of the front wall, *a*, of the fire-box is also separated into two parts, partly for the purpose of effecting equal circulation through the sides and partly to provide for the fire-door *j*; but I desire it to be understood that my invention is not limited to any particular contrivance of the coils for circulation, nor to the construction of the walls integrally or separately.

For a simple, cheap, efficient, and durable contrivance for the construction of the sectional boiler I propose to employ this same device of coils of pipe protected with an exterior 15 jacket of cast metal, and forming plates which may be so disposed in the make up of the boiler as to form return-flues by which the length of the run of the products of combustion may be extended within a short longitudinal 20 space and limited height to the utmost limit that will be beneficial for economy of heat.

The contrivance of these sections and the arrangement of the coils therein for circulation 25 may be varied to suit the nature and form of the boiler or other conditions; but an arrangement which I prefer consists of a plain coil of one range of pipes of suitable length and breadth, with a flange, *k*, along the margin of each edge on one side to rest on the furnace-wall or the section below for separating the several sections to provide the flue-spaces *l*, said flanges each having one length of pipe connected in the coil, and into one of 35 which, *m*, the water will be delivered from the stand-pipe *n*, while the other of said flange-pipes, *o*, will discharge into the hot-water or steam stand-pipe *p*, which discharges into the dome *q*. These sections, being superposed in 40 any desired number, will be dodged or staggered at the ends, as shown in Fig. 1, to form the return-passages *s* of the flues, in which the course of the products of combustion are indicated by the mutilated arrows, and the 45 water-circulation is shown by the arrows of complete form.

The ordinary return-bends, *t*, (shown in the two lower sections, Figs. 1 and 4,) may be employed in the construction of the coils, if desired, and they will preferably be covered with the jacket of cast metal, but for enabling the pipes of the coil to be opened for cleaning out, I propose to use a return-bend, *u*, of rectangular or other form, having a hand-hole 55 opening, *v*, in front of the ends of the pipes, through which the ends of the pipes may be expanded for making the connection of the pipes with the bends, and having a hand-hole cover, *w*, with which I propose to employ an 60 exterior plate, *x*, for holding the bolt *y*, that will completely cover the opening for providing a dead-air space, *z*, to economize heat, and will make one or more vents, *a'*, to allow of the escape of water in case any should leak 65 past the cover *w*.

In this case the cast-metal jackets will be stopped a little short of the ends of the pipes,

as shown best in Fig. 2, to allow the pipes to project sufficiently to connect the return-bends to them.

The boiler and furnace may of course be used without exterior covering, except to close the flues; but for economy of heat I propose to inclose it in a brick structure of suitable form, as represented in the drawings.

I am aware that plates have been made for use in boiler-furnaces by casting metal on coils of pipes for the circulation of water through the plates, and I do not claim such plates, broadly.

The furnace-walls and the rest of the boiler thus made of coils protected with cast-iron may be used with advantage for a hot-air furnace by admitting air to the coils instead of water; but it would be better to make the 85 coils of larger pipe in such case than is necessary for a boiler.

What I claim, and desire to secure by Letters Patent, is—

1. The combination, in a boiler-furnace, of 90 the front wall, *a*, side walls, *b*, bridge-wall, *d*, and the side walls, *c*, back of the bridge-wall, consisting of plates formed of coils of pipe incorporated with metal jackets cast upon the coils, and the coils being connected for the circulation of the water through the plates, substantially as described.

2. The combination, with a boiler, of furnace-walls consisting of coils of pipe incorporated with cast-metal jackets cast upon the 100 coils and forming plates, and said coil-plates having suitable connections for causing the circulation of water through them to the boiler, substantially as described.

3. Coil-plates for sectional boilers, consisting of a plain flat plate with a flange along the margins of one side to support the plates over a space for a heat-flue, said plates having the coil of pipes incorporated in the main body and in the flanges, substantially as described.

4. The combination, in a steam-boiler, of sectional flanged coil-plates of steam-pipe incorporated with cast-metal jackets, and furnace-walls, also consisting of coil-plates of steam 115 pipe incorporated with cast-metal jackets, said furnace-walls and sectional plates being suitably connected for the circulation of water and steam, substantially as described.

5. The combination, in a steam-boiler, of 120 furnace-walls consisting of plates formed of coils of pipe incorporated with metal jackets cast upon the coils, and a series of superimposed plain flat coil-plates having a flange along the margins of one side to support them 125 over spaces for heat-flues, said plates being alternately detached from and connected at the ends with the end walls of the furnace to form a flue extending along both sides of each plate, substantially as described.

JOHN S. PESSENGER.
